NECKLACE

Victor Manuel, 491 NW. 44th Ave.,
Fort Lauderdale, Fla. 33313

Filed Aug. 10, 1971, Ser. No. 170,675

Term of patent 14 years

Int. Cl. D11—01

U.S. Cl. D45—16 A

FIG. 2

FIG. 3

FIG. 1 is a front elevational view showing my new design for a necklace;

FIG. 2 is a side elevational view of the necklace shown in the FIG. 1 as seen from the left thereof with parts of the thongs being shown broken away;

FIG. 3 is a rear elevational view thereof;

FIG. 4 is a top plan view thereof;

FIG. 5 is a bottom plan view thereof; and

FIG. 6 is a side elevational view thereof as seen from the right of FIG. 1.

I claim:

The ornamental design for a necklace, as shown and described.
